COMBINED MATCH-HOLDER AND
AUTOMATIC LIGHTERWilliam Livingstone Roxburgh and Sydney
Brian O'Neill, London, EnglandApplication October 18, 1932, Serial No. 638,350,
and in Great Britain February 9, 1932

4 Claims. (Cl. 206—20)

This invention relates to combined match-holders and automatic lighters of the kind in which a number of matches are arranged so as to project and be readily withdrawn, and in which the act of withdrawing a match causes it to be automatically ignited.

The object of the invention is to provide an improved and simplified device of the above indicated kind.

10 The improved combined match-holder and automatic lighter according to the invention comprises a container of any desired outer form whether circular or angular having an inclined upper surface adapted to receive a number of matches in a recumbent and sloping position and provided with serrations or teeth which separate the matches and enable them to be withdrawn one by one, a recess running transversely to and at or near the upper edges of the serrations or teeth 15 and adapted to hold a band of striking paper or other material, and a cover or lid adapted to be secured in position upon and to hold the recumbent matches in normal position with sufficient pressure to cause them to come into contact with the striking surface on being withdrawn.

20 The improved device may be constructed in a circular, square, or any other desired form which allows the matches to be placed in the container side by side in a recumbent and slanting position.

25 A construction of the combined match-holder and automatic lighter according to the invention is illustrated in the accompanying drawing, in which

Fig. 1 is a central vertical section showing 30 matches in position, the view being also partly in perspective;

Fig. 2 is a plan of the device one half showing 35 the cover or lid in position and the other half showing the serrations or teeth in the container as seen when the cover is removed.

40 Fig. 3 shows in section a specific form of device in which the striking material is laid upon the recumbent matches.

45 Referring to the drawing, the container 1 in the example illustrated is made circular thus giving a dished formation to the inclined plane 2 which receives the matches 3. This inclined plane is provided with a number of radially arranged serrations or teeth 4 which project between and separate the matches 3 thus rendering it easy to withdraw the latter one by one when required.

50 A circular recess 5 is arranged near the upper edges of the serrations 4 and in this recess is inserted a ring 6 the inner part of the surface of

which is bevelled off as shown at 12 so as to be in alignment with the inclined plane of the dished container and to accommodate the recumbent matches. The bevelled ring 6, 12 is covered with an annular strip of striking paper or the like 60 material 13 which may be glued upon the top surface of the ring and which makes contact with the match heads and ignites the matches when they are withdrawn. In addition to the serrations or teeth 4 effectively separating the matches they 65 also prevent the ignition of one match from causing the ignition of the adjacent matches.

The cover or lid 7 consists of a plain disc having a dished form corresponding to the inclined upper surface 2 of the container 1. This dished form 70 of the cover or lid 7 may conveniently be utilized as an ash tray.

75 The cover 7 is secured in position by means of a bayonet bolt 8 having one or more projections 9 on its lower end which pass through a correspondingly grooved hole 14 in the central part of the container 1. In the device shown the bolt 8 is provided with a head 15 in the form of a cigarette holder which is secured to the bolt by means of a cotter pin 16. The cover 7 is adjusted in position by inserting the bolt 8 in the hole 14 and giving the bolt a quarter or slight fraction of a turn, thus automatically providing sufficient pressure upon the matches 3 to ensure that when they are withdrawn they come into frictional contact with the striking paper 13. For this purpose an inward bulge 10 of special formation is provided upon the underside of the cover 7 immediately opposite the recess 5 containing the ring of striking paper 13 so that the head of a match 80 on coming opposite the striking paper is forced with an additional pressure against the latter whereby the match is ignited with certainty. The ring 6 is yieldingly supported upon small cushion pads 11 (Fig. 1) which are equally spaced around 85 and in the circular recess 5, to enable the ring 6 to yield somewhat on being engaged by the match heads.

90 In a simplified construction the ring 6 and cushion pads 11 are dispensed with, the recess 5 is merely cut through the radial serrations or teeth 4, and a ring of striking paper 13a corresponding in its dimensions to the recess 5 is laid loosely over the matches within the upper part of the 95 said recess. In this form sufficient resiliency between the cover or lid and the matches can be obtained by providing a light compression spring between the head of the bolt and the cover or lid 7.

What we claim and desire to secure by Letters Patent is:—

1. A combined match-holder and automatic striker comprising in combination a circular container, a dished surface therein for the reception of a layer of matches, radial serrations symmetrically arranged upon said dished surface dividing each match from the adjacent match of the layer, an annular groove running transversely to and through the said serrations, a ring of striking material arranged in the groove beneath the recumbent matches in the container, cushion pads spaced from one another in the said groove resiliently supporting the ring of striking material, 15 a circular cover for the container and means for securing the cover in position.

2. A combined match-holder and automatic striker comprising in combination a container, a surface therein for the reception of the matches sloping from its inner edge upwards towards its outer edge, a set of projections upon said sloping surface dividing each match from the adjacent match, a groove running transversely to and through the said projections, striking material 20 arranged in the groove above the recumbent matches in the container, a cover for the container, and means for resiliently securing the cover in position.

3. A combined match-holder and automatic

striker comprising in combination a container, a surface therein for the reception of the matches sloping from its inner edge upwards towards its outer edge, a set of projections upon said sloping surface dividing each match from the adjacent match of the layer, an annular groove running transversely to and through the said serrations, a ring of striking material arranged in the groove above the recumbent matches in the container, a cover for the container, a thickened part of the cover opposite to the groove in the container adapted when in the closed position to press the striking material against the upper sides of the matches, and means for securing the cover in position.

4. A combined match-holder and automatic striker comprising in combination a circular container, a dished surface therein for the reception of a layer of matches, radial serrations symmetrically arranged upon said dished surface dividing each match from the adjacent match of the layer, an annular groove running transversely to and through the said serrations, a ring of striking material arranged in the groove so as to contact with the heads of the matches on the latter being withdrawn, a circular cover for the container and a centrally arranged bolt securing the cover in position.
